UNITED STATES PATENT OFFICE.

RICHARD DOWSE, OF CHICAGO, ILLINOIS.

CLOTHES-WRINGER ATTACHMENT FOR BATHTUBS.

1,382,415.

Specification of Letters Patent. Patented June 21, 1921.

Application filed September 25, 1919. Serial No. 326,138.

To all whom it may concern:

Be it known that I, RICHARD DOWSE, a citizen of the United States, residing at Chicago, in the county of Cook and State 5 of Illinois, have invented certain new and useful Improvements in Clothes-Wringer Attachments for Bathtubs; and I do declare the following to be a full, clear, and exact description of the invention, such as 10 will enable others skilled in the art to which it appertains to make and use the same.

This invention relates to clothes wringer racks or supports, and it has more particular reference to a rack which is especially designed 15 for attachment to an ordinary bath tub.

The principal object of the invention is to provide a clothes wringer attachment for 20 bath tubs which will enable the lady of the house to conduct her washing in her bathroom instead of going to the stationary wash tubs, which are usually in the cellar, and are in some instances, for instance in apartment houses, numerous floors down and not 25 at all convenient.

A further object of the invention is to provide an attachment of the above mentioned character in which the construction is such that it may be effectively placed in 30 position on bath tubs which are in close proximity to the bathroom wall.

Another object of the invention is to provide a device of the above mentioned character, which is exceedingly simple in construction, strong, durable, inexpensive, 35 highly efficient in use, and readily applicable to most any bath tub.

Other objects and advantages of the invention will become apparent during the 40 course of the following description.

In the accompanying drawings forming a part of this specification and in which like numerals are employed to designate like parts throughout the same,

45 Figure 1 is a cross section of a bath tub, illustrating my clothes wringer attachment applied thereto.

Fig. 2 is a top plan view of the attachment.

50 Fig. 3 is an end elevation thereof.

Fig. 4 is a transverse section on the plane of the line 4-4 of Fig. 2.

In the drawings, wherein for the purpose of illustration is shown a preferred embodiment

ment of my invention, the numeral 1 indicates a conventional form of bath tub, to which my improved clothes wringer support, designated as a whole, by the numeral 2, is attached and which supports a clothes wringer 3 of any usual or standard construction.

My improved wringer supporting attachment comprises a base board 4 which is adapted to be placed horizontally across the tub 1, and which is of a length to fit over any standard thirty-inch bath tub. A centrally disposed vertical wringer board 5 is nailed or otherwise secured to the base board 4, and this board 5 serves to permit the wringer 3 to be clamped thereon in any suitable manner. This board 5 is shorter than the base board 4 and at one end, the two boards are flush. The opposite end, however, of the wringer board is spaced from the end of base board 4 to permit the clamp 6 to be attached thereto as will be hereinafter more fully described. Connected to the opposite ends of the wringer board 5 in any suitable manner are a pair of transverse end plates 7 and 9 which extend upwardly and above the base board 4. These end plates 7 and 8, primarily serve to reinforce the structure, and they are also intended to prevent a portion of the water which drops from the wringer on the board 4 from flowing endwise off of said board and coming into direct contact with the wall or running on the bathroom floor. Instead of such endwise flowing of the water, these members 7 and 8 will tend to divert or 80 cause a portion of the water to run into the tub. The plate 8 is composed of a thin sheet of metal and a portion 9 thereof is extended below the base board 4, the extended portion of said plate being adapted for disposition between the rim of the tub 1 and the wall. In proceeding to explain the particular function of this metal plate, I wish 85 to emphasize the fact that careful study of a great many bathrooms has revealed the fact that the greater number of them are built with a view of utilizing as little space as possible, consequently one rim of the bath tub is in close proximity to the wall. With 90 this difficulty confronting the effective use of such a device, it would be almost impossible to clamp one end of the base board to the tub, because of the lack of space.

95

100

105

However, with a thin metal plate such as I employ, all the space that is needed is a space slightly more than the width of the plate. Whatever more space there may be 5 is immaterial, as the entire attachment will square itself by means of this plate 8, and the opposite end of the device will be held in place by means of the clamp 6 which co-acts with it and the rim of the tub 1. 10 Even in cases where the rim of the tub touches the wall, the device may still be placed in position by wedging the portion 9 of the plate 8 in place. This is not true with the majority of similar devices known 15 to me, as they usually employ some clamping means which would be useless where small space between the rim of the tub and wall is concerned.

It is to be understood that the form of 20 my invention herein shown and described is to be taken as a preferred example of the same, and that various changes in the shape, size and arrangement of parts may be resorted to without departure from the 25 spirit of the invention or the scope of the subjoined claim.

Having thus described my invention, what I claim is:

An attachment for supporting a clothes wringer on a bath tub comprising a horizontal base board adapted for transverse disposition on a tub, a centrally disposed vertical wringer board carried by the base board and having one of its ends flush with one end of the base board and its opposite 35 end spaced from the opposite end of the base board, a transverse cleat disposed at the last named end of the wringer board, a plate composed of a thin piece of metal, 40 said plate being perpendicularly disposed and secured to the flush ends of said boards, a portion of said plate extending above the base board and a portion extending below the bottom of said board, said last named 45 extended portion being adapted to be disposed between a wall and the rim of the tub, and means for fastening the opposite end of the base board on the tub.

In testimony whereof I have hereunto set my hand.

RICHARD DOWSE.
